VENDING MACHINE

Benjamin L. Fry, St. Louis, Mo.

Application February 12, 1935, Serial No. 6,241

8 Claims. (Cl. 194—39)

This invention relates to vending machines of that general class shown and described in my co-pending application, filed in the United States Patent Office, September 27, 1934, and bearing 5 Serial No. 745,823.

The object of the invention is generally to improve the construction of the machine and increase the efficiency thereof whereby positively to prevent unauthorized or fraudulent delivery of 10 merchandise.

A further object of the invention is to provide the coin carrier with a pivoted latch which normally locks the carrier against sliding movement on the carrier guide and which cannot be released until a coin of the proper weight, size and 15 denomination is inserted in the coin chute.

A further object is to provide means movable with the coin carrier for receiving a single cigarette or other article of merchandise from the magazine whereby to retain the cigarette or other 20 article in parallel relation to the forward edge of the carrier guide during the dispensing operation and thus insure positive and accurate delivery of said article without damage thereto or interfering with the proper functions of the machine.

A further object is to provide the coin carrier with lateral supporting lips disposed beneath the article holder and on which the cigarette or other 25 article drops when released from said holder and from which the article is ejected for delivery to a purchaser upon retraction of said coin carrier.

Other objects of the invention will appear as the description proceeds.

In the accompanying drawings forming a part 30 of this specification and in which similar numerals of reference indicate corresponding parts in all the figures of the drawings,

Figure 1 is a perspective view of a vending machine constructed in accordance with the present 35 invention.

Figure 2 is a rear elevation, the cabinet being open.

Figure 3 is a horizontal sectional view on the 40 line 3—3 of Figure 2.

Figure 4 is a horizontal sectional view on the line 4—4 of Figure 2.

Figure 5 is a vertical sectional view on the line 45 5—5 of Figure 2.

Figure 6 is an enlarged detail transverse sectional view of the plunger and its associated parts.

Figure 7 is a perspective view of the coin carrier and guide therefor separated but approximately in their proper positions.

Figure 8 is an enlarged detail vertical sectional

view showing the position of the parts as a coin enters the coin carrier.

Figure 9 is a similar view showing the coin fully inserted in the carrier and with the locking arms elevated or released and said carrier just starting 5 on its forward movement.

Figure 10 is a similar view showing the position of the parts on a further forward movement of the plunger and with one of the articles from the magazine within the holder. 10

Figure 11 is a similar view showing the position of the parts upon initial return movement of the plunger with the coin released and about to enter the coin receptacle and with one of the articles resting on the supporting fingers. 15

Figure 12 is a similar view showing the parts as the plunger approaches the limit of its return movement with one of the articles about to be ejected from the supporting fingers for delivery at the front of the machine. 20

As shown in the drawings, the machine comprises a cabinet including a back section or plate 5 having a flange or bead 6 along its edges and a front section 7 connected to the back by hinges 8 so that it may be swung open, as shown in Figure 2 of the drawings, to permit refilling of the magazines. The back plate is provided with openings 9 through which screws or other fastening devices may be inserted into a wall or fixed support, but it will be understood that the machine 30 may be mounted upon or secured to a pedestal or the like if desired. In closed position the front section of the cabinet fits closely within the flange 6 of the back plate and is secured by a lock 9, the key of which may be kept by the owner or 35 custodian of the machine.

The front section is preferably provided with glazed windows 10 for the display of labels or samples identifying the goods in the magazines behind the respective windows and a mirror 11 40 is preferably secured upon the front of the cabinet above the windows in order to give the machine an ornamental appearance. The front of the cabinet immediately below the windows is extended laterally to provide a ledge or step 12, 45 and coin chutes 13 are fitted through and secured in said ledge one below each window, said chutes being so designed as to admit a coin of the proper size, weight and denomination to operate the machine. Mounted on the inner 50 side of the wall of the cabinet behind each window is a magazine 14, the lower end of which fits within the upper end of a receiving chute 15, the magazines being properly positioned by lugs 16 on the cabinet wall and held against movement 55

at their upper ends by spring fingers 17. The lower end of each receiving chute 15 is open to permit the discharge of cigarettes or other articles therethrough and secured to the lower end 5 of each coin chute is a leaf spring 18. Arranged beneath each receiving chute 15 is a coin carrier guide 19 which may be stamped from a single integral sheet metal blank, said carrier being provided with lateral wings or shelves 20 having 10 transverse slots 21 formed therein and provided with pendent flanges 22 at the front edge of each shelf through which and the front wall of the cabinet securing bolts are passed. The material between the shelves or wings 20 is depressed to 15 form a trough or channel 23 in which the coin carrier slides, said coin carrier being indicated at 24. The side walls of the trough 23 are provided with horizontal slots 25 and its front wall with a vertical web 26 having a central opening 20 27 through which the operating plunger 28 reciprocates, there being a similar aligned opening provided in the front wall of the cabinet, as shown. Upon the floor of the trough 23 is a longitudinal rib 29 upon which the inserted coin 25 rides to drop into a seat 30 at the rear end of the rib and thus prevent return movement of the coin. Continued inward or rearward movement of the coin causes it to drop successively into a seat 31 and over the end of the trough into a 30 coin box or till 32 supported in any convenient manner below the coin guide. The rear edges of the supporting shelves or wings 20 are tilted upwardly, as indicated at 33, to retard movement of a cigarette or other article deposited thereon 35 and it will be noted that the transverse slots 21 intersect and open through the tilted edges 33 of the shelves 20, as shown.

The foregoing description delineates the construction of the vending machine shown and described in my co-pending application, previously referred to, with the exception of the transverse slots 21 in the carrier guide and I will now proceed to explain fully the improvements thereon constituting the subject-matter of the present invention.

Slidably mounted in each trough 23 is a coin carrier consisting of a block 34, the rear face of which is provided with a channel 35 adapted to receive a coin and the upper portion of the 50 wall of this channel is inclined or beveled at 36 so as to positively direct the coin into the channel. Projecting vertically from the front wall of the block 34 are spaced arms 36' preferably normally disposed slightly below and at the 55 rear end of the coin chute 13, the metal constituting said arms being extended laterally in a horizontal plane in opposite directions and bent upon itself to form an elongated holder 37 adapted to receive a single cigarette or article from 60 the magazine and hold said cigarette in parallel relation to the forward edge of the carrier guide during the dispensing operation and thus insure positive and accurate delivery of said article without damage thereto or interfering with the 65 proper functions of the machine. Extending forwardly from the holder 37 are cut-off fingers 38 which are movable to a position beneath the bottom of the magazine when the plunger is moved inwardly and serve to prevent the discharge 70 of the articles from the magazine while a single cigarette or other article is being dispensed from the holder 37. The cut-off members 38 are extended downwardly at the rear of the holder and thence laterally to form supporting fingers or ledges 39 on which the ciga-

rette drops when released from the holder and the purpose of the transverse slots 21 is to accommodate the intermediate portions of the members 38 during reciprocation of the coin carrier.

Coacting with the block 34 of the coin carrier is a pivoted latch 40, the front wall of which is normally disposed at an angle or inclination to the wall of the channel 35, said latch being provided with horizontally disposed locking arms 41 which coact with stop lugs 42 formed at the rear end of the trough 23 and serve to prevent sliding movement of the coin carrier until after a coin has been inserted in the slot 13 and drops into the channel 35 which action causes the coin 15 to tilt the latch and move the arms 41 out of the path of the lugs 42 so as to permit rearward movement of the carrier. When the coin has been discharged, the latch 40 will move by gravity to its normal position at an angle to the wall of the 20 channel 35 and with the locking arms 41 disposed in alignment with the lugs 42. The latch 40 is provided with spaced ears 43 and extending through said ears and into the block 34 are lateral pins 44 which act as pivot pins for the latch. 25 The outer ends of the pins 44 extend through the slots 25 in the carrier guide and serve to guide the coin carrier therein during reciprocation of said coin carrier. Retractile springs 45 are secured at their rear ends to the pins 44 and at 30 their front ends to the flanges 22, the pins thus serving as anchors for the springs, guides for the carrier, pivots for the locking latch, and by contact with the ends of the slots 25, as stops to limit the movement of the carrier. The free 35 ends of the supporting ledges or fingers 39 are preferably bent upwardly, as indicated at 46, so as to prevent displacement of a cigarette thereon until the coin carrier has been fully retracted.

Normally, the parts are in the position shown in Figure 5 of the drawings with the lowermost article in the stack disposed within the holder 37 and in contact with the up tilted edge 33 of the carrier guide. If a proper coin be inserted in 45 the coin chute it will pass into the slot or channel in the block 34, the spring 18 yielding but furnishing just enough resistance to guide the coin into said slot and this guiding of the coin is further effected by the beveled wall 36 of the 50 channel, as best shown in Figure 8 of the drawings. If a lighter coin or a cardboard disk be inserted, the spring will deflect it laterally out of the path of the slot or channel 35 without effecting the operation of the machine. A proper 55 coin being inserted, the weight of said coin will tilt the latch 40 on its pivot and allow the coin to come to rest on the guide rib 29 and in which position the locking arms will be elevated above the stop lugs 42 so as to permit inward movement of the carrier, as best shown in Figure 8 of the drawings. After depositing a coin, the customer pushes the plunger 28 inwardly, thereby causing the coin to drop into the seat 30 whereupon the rib 29 will prevent its withdrawal 60 or retrograde movement of the coin carrier. The inward movement of the plunger continuing, the coin will drop onto the seat 31. As the coin carrier moves inwardly, a cigarette or other article will be moved by the holder 37 rearwardly of the 65 machine and the cut-off fingers 38 will pass beneath the bottom of the magazine and prevent the further discharge of articles therefrom, as best shown in Figure 11 of the drawings. When the holder 37 reaches a position over the sup- 75

porting ledges or fingers 39, the article contained in the holder will drop onto and be supported by the fingers 39 and at the same time the coin will be ejected from the seat 31 and drop into the till 32, the discharge of the coin happening at the extreme end of the inward stroke of the plunger. When the coin is discharged, the springs 45 will retract the coin carrier and the cigarette or other article will roll off of the deflected ends 46 of the supporting fingers and drop onto an inclined plate 59 arranged beneath the till and in position to permit its easy removal at the discharge opening 51 of the machine. It will here be noted that after the coin has been discharged and the coin carrier is retracted, the pivoted latch 40 will assume its normal position at an angle to the wall of the channel 35 and thus again bring the locking arms 41 in position to coat with the stop lugs 42 and prevent further movement of the coin carrier until a coin of the proper denomination, size and weight has been inserted in the machine.

It will thus be seen that the machine cannot be operated unless a proper coin be inserted and the article will not be delivered until after the coin has dropped into the coin box so that two articles cannot be obtained by a single coin. It will, furthermore, be noted that inasmuch as the articles are successively delivered to the holder 37, which is of approximately the same size and shape as the article, and said article is carried by the holder to the point of delivery, it follows that there can be no lateral movement of the article while in transit which would tend to cause it to jamb and interfere with the proper functioning of the machine. While I have shown a machine especially designed and adapted for vending cigarettes one at a time, it will, of course, be understood that the machine may be used with equally good results for vending any other desired commodity either singly or in packages and I do not want the invention to be limited in this respect. It will, furthermore, be understood that the machines may be constructed with a single magazine or a gang of magazines and operated with a coin of any desired denomination.

Having thus described the invention, what is claimed as new is:

1. A vending machine including a casing, means within the casing for supporting a stack of merchandise, a guideway below the stack and provided with stop lugs, a coin carrier slidably mounted in the guideway and including a pivoted latch coating with the lugs for normally preventing sliding movement of the carrier, a coin chute for directing a coin into the carrier, an article holder movable with the carrier and provided with cut off fingers adapted to extend beneath the stack of merchandise when the carrier is in extended position, supporting lips depending from the holder and adapted to receive an article from said holder, means whereby the coin in the carrier will tilt the latch to permit sliding movement of the carrier and delivery of a single article from the holder onto the supporting fingers, and means to prevent discharge of the article from said supporting fingers until the coin is released.

2. A vending machine including a casing, means disposed within the casing for supporting a stack of merchandise, a guideway below the stack and provided with stop lugs, a coin carrier slidably mounted in the guideway and including a pivoted latch having locking arms coating with the lugs for normally preventing sliding move-

ment of the carrier, a coin chute for directing a coin into the carrier, an article holder movable with the carrier, supporting members carried by the holder, means whereby the coin in the carrier will release the arms from engagement with the lugs to permit sliding movement of the carrier and delivery of a single article from said holder onto the supporting members, and means to prevent discharge of the article from the supporting members until the coin is released. 10

3. A vending machine including a casing, means within the casing for supporting a stack of merchandise, a guideway below the stack provided with spaced stop lugs, a coin carrier slidably mounted in the guideway and provided with a coin receiving channel, said carrier including a pivoted latch normally disposed at an angle to the wall of the channel and provided with spaced locking arms coating with the stop lugs and normally preventing sliding movement of the carrier, one wall of the channel being beveled to direct a coin therein, an article holder movable with the carrier and provided with cut off members adapted to extend beneath the stack of merchandise when the carrier is in extended position, and means whereby the coin in the carrier will tilt the locking latch to clear the lugs and permit sliding movement of the carrier and delivery of a single article from said holder. 25

4. A vending machine including a casing, means within the casing for supporting a stack of merchandise, a guideway below the stack and provided with wings having transverse slots therein, spaced stop lugs on the guideway, a coin carrier slidably mounted in the guideway and including a pivoted latch having locking arms coating with the lugs for normally preventing sliding movement of the carrier, an article holder forming part of the carrier and provided with oppositely directed article cut off and supporting 40 fingers movable within the transverse slots, a coin chute for directing a coin into the carrier, means whereby the coin in the carrier will tilt the locking arms out of engagement with the lugs to permit sliding movement of the carrier and delivery 45 of a single article from the holder onto the supporting fingers, and means to prevent discharge of the article from said fingers until the coin is released.

5. A vending machine including a casing, means within the casing for supporting a stack of merchandise, a guideway below the stack provided with oppositely disposed slots and spaced stop lugs, a coin carrier slidably mounted in the guideway, a latch pivotally mounted on the carrier and spaced therefrom to form a coin receiving channel, said latch being provided with locking arms coating with the lugs to normally prevent sliding movement of the carrier, pins extending through the slots in the guideway and engaging 60 the carrier and on which the latch is pivotally mounted, springs forming a connection between the pins and guideway, an article holder movable with the coin carrier, a coin chute for directing a coin into the carrier, and means whereby the 65 coin in the carrier will tilt the latch to permit sliding movement of the carrier and delivery of a single article from said holder.

6. A vending machine including a casing, means within the casing for supporting a stack of merchandise, a guideway below the stack, spaced stop lugs on the guideway, a coin carrier slidably mounted in the guideway and including a block having a coin receiving channel therein, the upper wall of which is beveled, a locking latch 75

pivots on the block and normally disposed at an angle to the adjacent wall of the coin receiving channel, said latch being provided with spaced locking arms coacting with the stop lugs for normally preventing sliding movement of the carrier, a coin chute for directing a coin into said channel, an article holder movable with the carrier, cut-off fingers carried by the article holder and adapted to extend beneath the stack of merchandise when the carrier is in extended position, article supporting fingers extending laterally from the holder, means whereby the coin in the channel of the carrier will tilt the latch to release the locking arms and permit sliding movement of the carrier and delivery of a single article from said holder onto the supporting fingers, and means to prevent retrograde movement of the carrier until the coin is released.

7. A vending machine including a casing, means within the casing for supporting a stack of merchandise, a guideway disposed beneath the stack and provided with a central channel having terminal stop lugs, a coin carrier slidably mounted in the channel of the guideway and including a block having its face cut away to form a coin receiving channel, a latch pivotally mounted on the block and provided with spaced locking arms normally resting on the bottom of the guide channel and coacting with the lugs for preventing inward movement of the carrier, said latch being normally disposed at an angle to the wall of the coin receiving channel, an article holder movable with the carrier, a coin chute for directing a coin into the coin receiving channel, means whereby the coin in the coin channel will release the latch

to permit sliding movement of the carrier and delivery of a single article from said holder, means for preventing discharge of the merchandise from the magazine during delivery of the article from the holder, and means for preventing retrograde movement of the carrier until the coin is released. 5

8. A vending machine including a casing, means within the casing for supporting a stack of merchandise, a guideway below the stack provided with lateral wings having upwardly tilted terminals and provided with transverse slots opening through said tilted terminals, said guideway being provided with a central channel having spaced stop lugs at one end thereof, a coin carrier slidably mounted in the channel of the guideway 15 and including a block having a channelled face to receive a coin, a latch pivotally mounted on the block and normally disposed at an angle to said channelled face, said latch being provided with horizontal locking arms coacting with the lugs 20 to normally prevent sliding movement of the carrier, a holder movable with the carrier and adapted to receive a single article from the stack, supporting fingers carried by the holder, a coin chute for directing a coin into a channel of the 25 carrier, means whereby the coin in said channel will tilt the latch to permit sliding movement of the carrier and discharge of a single article from said holder onto the supporting fingers, means to prevent retrograde movement of the carrier 30 until the coin is released, and means for ejecting the article from the supporting fingers upon return movement of said carrier.

BENJAMIN L. FRY. 35
